INVENTOR,
Clement D. O'Rourke,
BY
Howard J. Smith
His ATTORNEY

UNITED STATES PATENT OFFICE.

CLEMENT D. O'ROURKE, OF DAYTON, OHIO.

NEWSPAPER BOX FOR STREET CARS.

1,412,417.

Specification of Letters Patent. Patented Apr. 11, 1922.

Application filed February 23, 1921. Serial No. 447,008.

To all whom it may concern:

Be it known that I, CLEMENT D. O'ROURKE, a citizen of the United States, residing at Dayton, in the county of Montgomery and 5 State of Ohio, have invented a new and useful Improvement in Newspaper Boxes for Street Cars, of which the following is a specification.

The object of my invention is to provide 10 for use in street cars, a box from which a newspaper may be withdrawn by a passenger upon the deposit of a coin or coins representing the price of said paper, in a separate compartment in the box. Many 15 passengers riding to and from their homes on street cars, board them at places where newspapers cannot be secured. For them my box is a special convenience, for it enables them to read while they ride, and at 20 the same time permits the newspaper publisher to dispose of his papers at less cost than by newsboy or carrier. The box may be mounted at any place in the car that makes it readily accessible to the incoming 25 or outgoing passengers.

Other important and incidental objects will be brought out in the following specification, and particularly set forth in the subjoined claims.

30 In the accompanying drawings, Figure 1 is a front elevational view of my box for street cars. Figure 2 is a longitudinal section taken through the same on the line *a—a* of Figure 1. And Figure 3 is a perspective view of the interior of a street car, showing my box mounted near the exit door.

Throughout the specification and drawings, similar reference characters denote corresponding parts.

40 In a detailed description of the preferred form of embodiment of my device, the numeral 1 designates a box preferably constructed of metal. The box has a preferably rectangular front wall 2 that may contain 45 any suitable legends, such as those shown on it in Figures 1 and 3. The rear wall 3 of the box is also rectangular in shape, and rises a substantial distance above the horizontal plane of the top of the front wall 2. 50 The box has a flat bottom 4, and side walls 5, 5 whose top edges incline downwardly from the top of the rear wall 3 of the box to the top of its front wall 2. (See Figure 3). The box is divided into a newspaper

receiving compartment and a coin receiving 55 compartment as follows:

Set adjacent one side wall 5 of the box, upon the bottom 4 between its front and rear walls 2 and 3 respectively, is a partition piece 6 having a right-angled top part 60 7 whose outer edge portions are soldered or otherwise secured to the side, front and end walls surrounding it.

The space in the box 1 between the outer 65 face of the partition 6 and the opposite side wall 5, is adapted to receive newspapers folded upon themselves as shown in Figure 3. Each newspaper projects a sufficient distance above the front wall 2 of the box to be readily accessible for withdrawal therefrom 70 by a passenger who, in payment therefor, will drop the necessary coin or coins through a chute 8 that is set within a hole in the right-angled top portion 7 of the partition 6. These coins will then drop 75 through the space between the inner face of the partition 6 and the adjacent wall 5, into a small drawer 9, which rests upon rails 10 mounted on the bottom 4 of the box. This drawer may be readily moved over these 80 rails into and out of the lower portion of the coin receiving compartment, through an opening in the lower right hand corner of the front wall 2 of the box, and locked in its innermost or coin-receiving position by 85 a key 11 that is insertible in a lock 12 in the front portion 13 of the drawer. By unlocking it, the drawer 9 may be withdrawn periodically from the box to remove the 90 coins that have accumulated therein.

To prevent the coins from falling between the sides of the drawer 9 and the sides of the coin receiving compartment, curved deflecting strips 14 are provided, one of which is soldered to the partition 6, another 95 to the side wall 5 and another to the rear wall 3 above the drawer, to direct the coins thereto. (See Figures 1 and 2).

By means of screws 15 passed through holes in the top portion of the rear wall 3 of 100 the box, the latter may be firmly secured to the frame 16 of a street car in any position which will permit the ready removal of the newspapers from said box by the passengers. Other suitable means, however, may be provided for mounting the box in a street car 105 without departing from the spirit of my invention.

Having described my invention, I claim:

1. A box adapted to be mounted within a street car, comprising a bottom and four walls, a partition between the front and 5 rear walls and near one of the side walls, dividing said box into a wide newspaper holding compartment and a narrow coin receiving compartment, and a drawer movable through an opening in the front wall of the 10 box, into the bottom of the coin receiving compartment thereof.

2. A box adapted to be mounted within a street car, comprising a bottom and four walls, a partition between the front and 15 rear walls and near one of the side walls, dividing said box into a newspaper holding compartment and a coin receiving compartment, a right-angled top on said partition engaging the adjacent side wall, and the

front and rear walls, and a chute in a hole 20 in said partition top through which coins may be dropped into the compartment below for the purpose specified.

3. A box adapted to be mounted within a street car, having a newspaper holding compartment and a coin receiving compartment, a drawer movable in the coin receiving compartment, and deflecting strips secured to the walls of the latter above the drawer, to prevent the coins falling between the sides 25 of said drawer and the sides of the coin receiving compartment.

In testimony whereof I have hereunto set my hand this 21st day of February, 1921.

CLEMENT D. O'ROURKE.

Witness:

HOWARD S. SMITH.
